UNITED STATES PATENT OFFICE.

CARL F. HOFFBAUER, OF MONTCLAIR, NEW JERSEY, ASSIGNOR OF ONE-HALF TO
IB NYBOE PASGAARD, OF NEW YORK, N. Y.

WEATHER STRIP.

Application filed May 29, 1925. Serial No. 33,642.

To all whom it may concern:

Be it known that I, CARL F. HOFFBAUER, a citizen of the United States, residing at Montclair, in the county of Essex and State 5 of New Jersey, have invented certain new and useful Improvements in Weather Strips, of which the following is a specification.

This invention relates to devices which are adapted for use in connection with windows 10 and doors or the like to keep the wind and weather out of dwellings and similar closures.

Among the objects of this invention is to provide a weather strip which is readily attachable to a door, or window or the like to prevent undesired circulation or leakage of wind or weather through the clearances which occur in doors and windows, said weather strip being provided with means to 20 prevent the rattling or objectionable singing noises which occur in weather strips that are in use at the present time.

Another object of this invention is to provide a weather strip which is readily attachable to a door or window and which is of neat and simple construction so as to be adapted to occupy as little space as possible and to be wholly inconspicuous.

Still another object of this invention is 30 to provide a composite weather strip structure which is adapted for such general use as may be desired and particularly in connection with windows, said structure comprising a guide member which is intended 35 to co-operate with a window in a conventional manner, and a resilient strip secured to said guide to provide a weather tight joint, both the guide and the strip being preferably marketed as a commercial unit.

With the foregoing and other objects in view the invention consists in the arrangement and combination of parts hereinafter described and claimed, and while the invention is not restricted to the exact details of 45 construction disclosed or suggested herein, still for the purpose of illustrating a practical embodiment thereof, reference is had to the accompanying drawings in which like reference characters designate the same parts 50 in the several views, and in which—

Figure 1 is a sectional view showing a typical installation of my device in connection with a window.

Fig. 2 is a perspective view of a portion 55 of the composite weather strip.

Fig. 3 is a sectional view showing the application of my invention to a door in open position and in dot-dash lines in closed position.

Referring now more particularly to the drawings, I show my invention in use in connection with a sash 10 or the like which is mounted in the usual sliding position within a window 11. Means are provided for guiding a side rail 12 of said sash including the vertical strips 13 adjacent to which a space is provided within the window for the reception of counterweights for the sash in a conventional manner. A parting strip or central guide 14 is provided to form a plurality of tracks for the sashes, said parting strip having suitable co-operation with the window as by direct abutment with the strips 13. Co-operating with the window I provide resilient weather strip means 15 to keep out the wind and weather which leaks through the clearances that are always observed in windows for the sake of easy 20 operation of the same. Said resilient strips are arranged for direct co-operation with the side rails of the sashes, or such other portions thereof as may be desired, and are arranged to lie in relative proximity or in substantially parallel relation to a portion 25 of the window structure. Preferably, however, said weather strips are mounted upon the central guide 14 and may be considered as being of unitary construction therewith. Thus said strips may be secured to said 30 guide by means of suitable fasteners 16 or the like so as to be marketed as a commercial unit with said guide, forming what is 35 in the nature of a composite weather strip.

Each resilient strip comprises a flange or body portion which is suitably curved in cross section to bridge the maximum clearance or gap that may occur in practice, said body portion being bent to lie within an edge portion 17 thereof in contact with the side rail 12, while the opposite edge of said body is provided with a flange 15^a or the like which seats against the inner edge of the guide 14 and is secured thereto by means of said fasteners. Said fasteners are thus wholly concealed within the window where 40 they are out of the way, and will not prevent the proper fitting of the guide within the window, while a portion of the body strip lies snugly between said guide and the adjoining portion of the window.

In order to secure the proper stiffness of the resilient strip, I provide it with an enlarged portion or bead 17 at said free edge thereof, said bead being in direct contact with the sash. I have found that the wind has a tendency to cause resilient strips of whatever nature which are used in connection with windows or the like to vibrate unduly and produce a sound or tone and that 10 humming noises frequently occur due to the vibration of the resilient strip which are highly objectionable. To eliminate such vibrations, I provide cushioning means such as a fabric or cord 18 within said bead. This 15 not only tends to strengthen the bead, but also eliminates vibrations by providing a dead body.

To provide a space within which said bead may be received, I form the rabbet 19 along 20 the guide 14, so that when the weather strip is used in the usual manner herein provided for, and with a body portion that comprises a single flange structure which in operative position is substantially flat and lies in substantially parallel relation to a side of the rail 12, said bead will be pressed into said rabbet. In this manner a neat and conventional appearance of the guide 14 is secured, as when the window is closed, and 30 the clearance required for the proper operation and actuation of the resilient strip is reduced to a minimum.

My composite weather strip will thus be seen to comprise a guide or supporting member which carries headed contact strips on each side thereof and which is rabbeted adjacent to each of said strips to provide clearances for the reception of the beads. It 35 will be understood that in each of these commercial units, the contact strips are for the sake of economy of material extended along the guide only for substantially half the length of the guide, while the guide is of sufficient length to be mounted for approximately 40 the full length of the window in a conventional manner. More specifically, the strip which co-operates with the lower sash extends from one end of the guide somewhat past the mid-point thereof, while the strip which co-operates with the upper sash lies upon the opposite side of the guide and 45 extends from the opposite end thereof past the mid-point of the guide. The portions of the strips which extend beyond the mid-point of the guide as aforesaid provide for continuous contact engagement of the strip and the sashes so that the necessary smooth operation is secured in sliding the sashes up and down. Thus as shown in Fig. 2 one

of the contact strips extends beyond the line 60 *a* which indicates the mid-point of the composite guide structure and terminates at 20, while the other extends beyond said line in the opposite direction and terminates at 21.

It will be seen likewise that the strips 13 65 are readily removable for access to the counterweights or other parts within the window without difficulty and without disturbing the parting strip or composite weather strip structure.

In Fig. 3, I show a modified installation of my resilient weather strip as used in connection with a door 22 and a jamb 23. Said strip 15^b is secured to said door at the free edge thereof and in such manner that the 75 beaded portion 17^a of said strip is arranged to contact the jamb when the door is closed as shown in dot-dash lines. Thus when the door is open, said bead will extend outwardly of the free edge of the door to any suitable extent and according to the space between the door and the jamb, while when the door is closed said bead passes over the edge of the door and lies adjacent to a side thereof provided a minimum space is found 80 between the door and the jamb. The strip may thus be secured to the door in a neat and efficient manner without changing the construction of the door or the jamb, and to be wholly inconspicuous especially when the 85 door is closed, in which case a rather attractive finishing touch is provided for the edge of the door.

My invention is capable of application to doors and windows in numerous ways, and 95 I have sought to indicate herein but the general principle and typical manner of application of the same.

I claim:

The herein described composite weather 100 strip comprising a supporting member, a pair of resilient strips extending along said member upon opposite sides thereof and secured to said member, the free edges of said strips being beaded and spaced from said member to contact a second member movable relatively thereto, one of said strips extending from an end of said supporting member past the mid-point thereof, while the other strip extends from an opposite end of said member and terminates at a point somewhat beyond said mid-point, the beaded portions of said strips being associated with cushioning means therein whereby the vibrations of 110 said strips are eliminated.

In testimony whereof I affix my signature.

CARL F. HOFFBAUER.
